(57) **CLAIM**

The ornamental design for a card, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a card showing our new design with a color scheme;

FIG. 2 is a front plan view thereof;

FIG. 3 is a back plan view thereof;

FIG. 4 is a top elevation view thereof;

FIG. 5 is a bottom elevation view thereof;

FIG. 6 is a left side elevation view thereof;

FIG. 7 is a right side elevation view thereof;

FIG. 8 is a front perspective view of a second embodiment of the card showing our new design in grayscale;

FIG. 9 is a front plan view thereof;

FIG. 10 is a back plan view thereof;

FIG. 11 is a top elevation view thereof;

FIG. 12 is a bottom elevation view thereof;

FIG. 13 is a left side elevation view thereof; and,

FIG. 14 is a right side elevation view thereof.

The dashed broken lines in the figures illustrate portions of the card that form no part of the claimed design.

1 Claim, 6 Drawing Sheets
